Pierre Barnes
ATTORNEY

UNITED STATES PATENT OFFICE.

EDWARD L. HOLMES, OF SEATTLE, WASHINGTON, ASSIGNOR TO PRINTING TRADES MANUFACTURING COMPANY, OF SEATTLE, WASHINGTON, A CORPORATION OF WASHINGTON.

LINOTYPE-MOLD.

1,337,358.

Specification of Letters Patent. Patented Apr. 20, 1920.

Application filed August 13, 1919. Serial No. 317,179.

To all whom it may concern:

Be it known that I, EDWARD L. HOLMES, a citizen of the United States, residing at Seattle, in the county of King and State of 5 Washington, have invented certain new and useful Improvements in Linotype-Molds, of which the following is a specification.

This invention relates to linotype molds in which typebars or slugs are cast.

10 In the operation of a linotype machine, the alternate heating and cooling of the mold effects the expansion and contraction thereof which produces local or unequal tensile and compressive strains which tend 15 to warp the mold and render it unsuitable for good work.

The object of the present invention is the improvement of linotype molds for the purpose of obviating the above mentioned 20 warping and other difficulties.

The invention consists in the novel construction and adaptation of devices as will be hereinafter described and claimed.

In the accompanying drawings, Figure 1 25 is a front elevational view of a linotype-mold embodying my invention. Fig. 2 is a rear elevation of the same. Fig. 3 is a fragmentary plan view thereof. Fig. 4 is a sectional view through 4—4 of Figs. 1 and 2.

30 In said drawings, the reference numeral 5 designates the body member and 6 the cap member of a mold which are retained in spaced relations by means of liners 7 to afford the slot 8 in which a linotype or slug

35 is cast. Adjacent to the slot 8, said body is formed with a bar element 5¹ of a width equal to the depth of the slugs, and below such bar portion the body is provided with a depending flange 5² provided with spaced 40 holes 9 for the reception of bolts, not shown, by which the mold body is rigidly secured to the mold wheel or disk of a linotype machine, as usual.

The cap member 6, in like manner, is provided with a bar element 6¹ which is formed integral with an arcuate rib element 6². The bar elements 5¹ and 6¹ constitute the lower and upper walls, respectively, of the mold slot 8.

50 The mold as above described is similar to those in general use on linotype machines.

According to the present invention, a recess 10 is provided in the underside of the body bar element 5¹ at the rear and at about 55 the midlength of the member.

A recess 11 is in like manner provided in the rear and centrally of the cap rib element 5² and extending, desirably, to within a short distance of the slot 8. The recesses 10 and 11 are of lengths of one-third, approximately, that of the mold. The function of said recesses is to provide cavities for the admission of air to facilitate the cooling of the mold subsequent to the slug casting operation.

In carrying out the invention the flange portion 5² of the body and the rib portion 6² of the cap are respectively provided with slits 13 and 12 extending from the bar portions 5¹ and 6¹ at right angles, preferably, to the mold slot 8.

As shown, the slits 12 of the cap rib are located in proximity to the ends of the recess 11 thereby dividing the rib into a recessed central portion 14 directly above the part of mold slot which becomes extremely hot when the molten metal is forced thereinto, and two wing portions 15 of a substantially triangular shape longitudinally of the cap. The slits 13 of the body member 5 are located intermediate the bolt holes 9.

The body flange is thus divided into a plurality of portions 16, each of which is arranged to be secured to the mold disk by a single bolt passing through the respective holes 9 so that the material in each portion may contract or expand independently of the other portions.

By reason of the slitting of the respective flange and rib elements the associated bar elements 5¹ and 6¹ may extend or contract without becoming warped or bent as would occur if constrained unslotted flange or rib elements such as hitherto used in linotype molds.

What I claim, is—

1. A slotted linotype mold consisting of complementary body and cap members provided with transversely arranged slits extending from the lower and upper edges respectively of said members into the proximity of the lower and upper walls of the mold slot.

2. A linotype mold having cavities in its body and cap members, said cap members slotted at their lower and upper sides respectively to afford portions which are expansible by heat individually for the purpose of obviating any warping of the mold.

members when subjected to varying temperatures.

3. A linotype mold having body and cap members which are slotted from their lower and upper sides, respectively, and at approximately right angles to the mold slot to afford longitudinally spaced portions in each of said members, thereby permitting expansion and contraction of the various portions without warping the respective members.

4. In a linotype mold, the combination with the body member, of a cap member having bar and rib elements, said rib element consisting of a plurality of spaced portions connected together through the medium of the bar element.

5. In a linotype mold, a body member having a bar element and a flange element divided by slits to afford spaced portions depending from said bar element, each of said flange portions being provided with a hole to receive a bolt for securing said member to a mold-disk.

25 6. A linotype mold having complementary body and cap members, respectively provided with bar elements which constitute

the lower and top walls of the mold slot, said body and cap members being provided with slits disposed respectively subjacent to 30 and above the bar elements thereof, and recesses provided in the bar element of the body member and in the cap member above the bar element thereof, said recesses being disposed at substantially the mid-length of 35 the mold.

7. In a linotype mold the combination with the body member having a bar element and a plurality of depending flange portions arranged in spaced relations with respect 40 to each other, of a cap member having a bar element and a rib element extending upwardly therefrom, said rib element being divided by slits to provide a central portion and two wing portions, said central portion 45 being recessed to afford a cavity for the admission of cooling air therewith.

Signed at Seattle, Washington, this 31st day of July, 1919.

EDWARD L. HOLMES.
